UNITED STATES PATENT OFFICE.

ALBERT CHARLES COUCH, OF BOSTON, MASSACHUSETTS.

SWEAT-BAND FOR HATS.

SPECIFICATION forming part of Letters Patent No. 291,157, dated January 1, 1884.

Application filed November 22, 1883. (No model.)

To all whom it may concern:

Be it known that I, ALBERT C. COUCH, a citizen of the United States, and a resident of Boston, Suffolk county, Massachusetts, have invented certain new and useful Improvements in 5 Sweat-Bands for Hats, &c., of which the following is a specification.

My invention is a sweat-band for hats, caps, &c., in whole or in part of gelatine, constituting a cheap and efficient substitute for the leather and oil-cloth heretofore in common use.

In the drawings, Figure 1 is a perspective view, illustrating the manufacture of my improved sweat-band. Figs. 2 and 3 are sectional views, illustrating the mode of connecting the band in the hat. Fig. 4 is a view showing a modification.

It is well known that ordinary cheap sweat-linings of common split leather soon absorb 20 perspiration and become soiled and offensive. Enameled fabric is more effective, but is also more expensive, and in time loses its efficiency.

To provide a most effective substitute for 25 these substances, I use gelatine combined with alum, chromic acid, or other substance, whereby it is rendered insoluble in water, form it into sheets, and cut the sheets into strips, which are bent and secured within the hat.

To facilitate the connection of the strip A, 30 of chromatized gelatine, to the cap, I cement to the outer side thereof a strip, a, of fabric, with one edge, b, projecting below the strip A, and the edge is folded to inclose a cord, c, as shown 35 in Fig. 2, which is sewed in place, and this corded edge serves as a means of connecting

the band in place by stitching, as shown in Fig. 3. The sweat-band thus formed is hard but thin, smooth, flexible, and little affected by moisture, will not become saturated with 40 perspiration like leather, and will not crack and wear like enameled cloth.

It will be apparent that although I have shown one means of connecting the insoluble gelatine strip in the hat others may be employed, and that the gelatine strip may constitute the backing of sheets of other material, as silk oil-cloth, &c.

It will also be apparent that a strip of other material, as silk oil-cloth, may extend partly 50 inside the gelatine strip, as shown in Fig. 4, where the strip a, lining the inside of the gelatine strip, also serves as a means of uniting the latter to the hat.

I claim—

1. A sweat-band for hats, consisting, in whole or in part, of a strip of insoluble gelatine, substantially as set forth.

2. The combination, in a sweat-band for hats, of a strip of insoluble gelatine and a connecting strip of fabric, substantially as specified.

3. The combination of a hat or cap and a sweat-band consisting of a strip of insoluble gelatine connected within the hat, substantially as specified.

In testimony whereof I have signed my name to this specification in the presence of two subscribing witnesses.

ALBERT CHARLES COUCH.
